Primary Examiner — Samantha Wood(74) *Attorney, Agent, or Firm* — Xiaofang Zhong; Law Office of Xiaofang Zhong, PLLC(57) **CLAIM**

The ornamental design for a faucet handle, as shown and described.

DESCRIPTION

FIG. 1 is a perspective view of a faucet handle showing my new design;

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines in the drawings depict part of the faucet handle that form no part of the claimed design.

1 Claim, 5 Drawing Sheets(56)
